TWO INSULATOR HIGH TENSION SWITCH

Ernest E. Anderson, Chicago, Ill.

Application July 17, 1929. Serial No. 378,848

28 Claims. (Cl. 200—48)

This invention relates in general to a switch for opening and closing an electrical circuit, and more particularly to a vertical break, two insulator, high tension, disconnecting switch.

In the past, disconnecting switches for use in high tension switching have been supplied by manufacturers, for mounting with their bases vertical, or horizontal in which case the insulators are either above the base or underslung below the base. With switches of this type the maintenance is very high as each type of mounting constitutes a different switch, which could not be adapted for a different mounting without the use of additional parts. In cases of emergency, this is a very undesirable condition as it is common practice to move electrical equipment from one location to another. For example, if a switch were mounted in one position at a given location and it was desired to move it to another location where it would have to be mounted in a different position; it could not be mounted in the new location without the addition of new parts.

Another objection to disconnecting switches, as they are presently made, is to the construction of the contacts. In the usual form, the contact is made between ground surfaces which soon get out of alignment, with the result that the original surface contact becomes a line or point contact and the ampere carrying capacity is greatly decreased. In order to adapt the usual contact for outdoor service, where extreme weather conditions are met with, it becomes necessary to provide sleet hoods or other means for protecting the contacts to assure the operation of the switch.

In the operation of high potential disconnecting switches, it often becomes necessary to open them under load. Due to the relatively small interrupting capacity of such switches and their slow speed of opening, the contacts become damaged from the arc which is established when the contacts begin to open.

Where the arc is broken between contacts in a hermetically sealed tube containing an arc extinguishing fluid, it has been a difficult problem to find a satisfactory way of sealing the tube into the end ferrules and making a final seal after the fluid is put into the tube. A tube of this type is subjected to extreme temperatures and pressure with the result that the glass either breaks where it is sealed into the ferrules or the tube leaks around the final sealing plug.

It is an object of this invention to provide a disconnecting switch which is adapted for mounting in any position simply by a reassem-

bly of the switch parts without the necessity of adding new parts.

It is another object of this invention to provide a full floating contact, which will be self aligning, have a multiplicity of positive contact points and maintain its ampere carrying capacity over a long period of time, and adapted for outdoor or indoor use.

It is also an object of this invention to provide a disconnecting switch which will open the electrical circuit in a very short period of time; the circuit being initially opened by a switch blade which carries the main current, and finally by a fluid switching unit which carries the secondary current and is in parallel with the switch blade.

It is a further object of this invention to improve the method for sealing the container which encloses the contact mechanism and which is filled with an arc extinguishing fluid.

Other and important objects of this invention will be apparent from the disclosures in the specification and the accompanying drawings.

This invention in a preferred form is illustrated in the drawings and hereinafter more fully described.

On the drawings:

Figure 1 is an elevational view including partial sections through the fluid break switch.

Figure 2 is an elevational view showing the switch mounted in a horizontal and vertical plane.

Figure 3 is a plan view of the switch.

Figure 4 is an elevational view showing the switch mounted in a horizontal plane with the insulators beneath the base.

Figure 5 is an enlarged fragmentary view showing the locking means and contact in section.

Figure 6 is an elevational view of the fluid break switch having broken away sections showing the position of the contact elements when the switch is mounted in an underslung position.

Figure 7 is an elevational view of the fluid break switch having broken away sections showing the position of the contact elements when the switch is mounted in a vertical position.

Figure 8 is an enlarged transverse section through the fluid break switch, line VIII—VIII in Figure 6.

Figure 9 is an enlarged transverse section through the contact of the air break switch taken on line IX—IX in Figure 4.

Figure 10 is a view showing the concentric grooves around the sealing hole and on the sealing screw.

110

Figure 11 is an enlarged fragmentary section through the final sealing means.

Figure 12 is a fragmentary sectional view showing the details of the floating mounting of the 5 switch blade contact support casting, taken substantially on line XII—XII of Figure 5.

As shown on the drawings:

The disconnecting switch, as a whole, is shown in Figure 1 mounted in a horizontal position with 10 the insulators above a mounting base 1. Insulator pins 2, which support the conventional type of high tension insulator 3, are secured to the top of the mounting base near its ends, by means of bolts 4 which extend through the base of the 15 insulator pin, the mounting base, and a plate 5. This plate makes it possible to secure the cap end of the insulator to the mounting base, by means of the cap bolts 6, when the disconnecting switch is mounted in the underslung position 20 as shown in Figure 4. In the mounting shown in Figure 1, a hinge terminal casting 7 is secured to the insulator cap by the cap bolts 6, and includes a lug 8, which is drilled for terminal connection to the power line, and the stationary 25 member 9 of the switch blade hinge. The movable member of the hinge comprises a casting 10, which is pivotally secured, by means of the pivot pin 11, to the stationary hinge member 9, and is bored and threaded to receive a blade 30 bar, or tube 12, which is clamped therein, by means of a clamping bolt 13. The electrical circuit is completed around the hinge by the flexible conductor 14 which is secured by the bolt 15 to the stationary member of the hinge and by 35 the bolt 16 to the lug 17 forming an integral part of the casting 10. It is therefore apparent that by using this construction, blade bars of varying length may be used; the hinge terminal casting and the blade hinge casting with its flexible 40 connector being common to voltages from 7500 to 73000 volts. For higher voltages castings of heavier construction would be used. The blade bar 12 is shown as being circular in design, but may be of any shape or form depending upon the 45 amount of current it must carry and the mechanical strength required.

The contact end of the blade bar 12 is threadedly secured to a forked casting 18 and securely clamped by means of a clamping bolt 19. This 50 casting 18 carries a full floating contact support casting 20, Figure 5, and a switch lock 21 having a pull ring 22 on its upper end and a latch dog 23 on its lower end, which engages with a contact casting 24. The switch lock 21 is 55 pivotally secured to depending lugs 25 of the forked casting 18, by means of a pin 26. The switch blade end of the casting 18 is drilled to receive a cylindrical member 27 having inserted therein for longitudinal movement a plunger 28, 60 which is forced outwardly by a spring 29, against the switch lock 21, which will be rotated in a clockwise direction until the stop pin 30 strikes against the lower edge of said casting 18. This 65 switch lock will therefore lock the switch blade in a closed position and prevent the switch from being forced open by a short circuit.

The full floating contact support casting 20 is 70 floatingly supported in the forked casting 18, as shown in Figure 12, by means of pin 31 and the pin 32a, the ends of which extend into oversize holes in the prongs of the fork casting. The longitudinal movement of the pin 32a is limited by short bolts 32 which are threaded into the oversize holes and abut against the ends of said 75 pin. The electrical circuit is completed from the

contact support casting to the forked casting by means of a flexible conductor 33, which is solidly bolted to the respective castings by bolts 34, 32 and 35. Integral with the contact support casting 20 is a projection 36 which is drilled and tapped to receive either the contact sheath 37 or the contact plunger 38. This interchangeability gives a contact, thoroughly housed against weather in all positions in which a switch is usually mounted. The contact casting 24 is secured to the insulator by the cap bolts 6 and is drilled and tapped to receive either the contact plunger 38 as shown in Figure 5 or the contact sheath 37. An integral lug 39, which is similar to the lug 8, is drilled for terminal connection to the power line.

The female member of the contact comprises a sheath 37 having a plurality of sockets 40 for receiving conducting spheres 41, which are backed up by connector straps 42 solidly fastened to one end of the sheath by screws 43. These conductor straps are enclosed by a cylindrical close wound coil spring 44, which exerts spring pressure on the spheres, forcing them to the bottom of their respective sockets where their further movement is arrested by an inturned edge of the socket. It will be noted that in this position the spheres project slightly past the inner wall of the sheath and make contact with the contact plunger 38. The entrance end of the contact sheath engages with an end member 37a containing a tapered orifice, which forms a guide for the contact plunger as it enters the female member of the contact. The contact sheath is enclosed by a cylindrical tube 45 which is securely fastened by means of the screws 46; at one end to the sheath and at the other to the end member 37a, thereby holding said end member in engagement with said sheath. This cylindrical tube therefore protects the contact mechanism from the weather elements. It is to be observed that when the contact plunger enters the contact sheath, it forces the conducting spheres outwardly against the connector straps, which in turn are forced firmly against the enclosing spring; this spring being free to weave or float together with the connector straps and spheres. The result is that each sphere is under spring pressure and forms a pressure contact between each sphere and the contact plunger as well as between each sphere and its connector strap. The spheres being free to roll or float in their respective sockets, a wiping contact is secured, thus insuring a multiplicity of clean contact points each of which has a definite current carrying capacity. The capacity of the contact is therefore proportional to the number of points of contact, and permits a definite current rating to be given the contact.

By the use of the full floating contact support, the plunger is reciprocally or laterally withdrawn from the contact sheath by the rotary motion of the switch blade about its hinge pivot. The full floating contact support permits the plunger to freely assume its position with reference to the full floating contact spheres, connector straps and the cylindrical close wound coil spring in the contact sheath. This feature compensates for any misalignment of the switch parts and the point of contact of each sphere is assured.

A fluid switching unit is supported on one end by a projecting arm 46 which is integral with the hinge casting 10, and on the other by a rotatable link 47 pivotally secured by a pin 47a to

the contact casting 24. The respective ends of the fluid switching unit are designated by A and B. A supporting and terminal casting is provided at the A end of the fluid switching unit comprising an annular ring 48 and depending arm 49 pivotally secured to the arm 46 by means of a bolt 50. The B end of the fluid switching unit has a similar supporting and terminal casting consisting of an annular ring 51 with a similar depending arm 52 pivotally secured to the link 47 by means of a bolt 53. Solidly bolted connections are provided at each end respectively by a flexible conductor 54 having one end secured to the arm 49 and the other to the arm 46 by the screw 55; and a flexible conductor 56 having one end secured to the arm 52 and the other to the contact casting 24 by one of the cap bolts 6. The contact mechanism is hermetically sealed within a tube 57, preferably of a vitreous material but not necessarily, which is filled with an arc extinguishing fluid (not shown on the drawings). Each end of the tube is sealed into a ferrule 58, the outer end of which is closed, having an outwardly extending flange which engages the annular ring of its associated supporting and terminal casting and is secured thereto by means of screws 59. The ferrule on the end B is drilled and tapped to receive the hermetic sealing screw 60, Figure 11. The base and seat of this screw are provided with concentric grooves (Figure 10) so that when the screw is tightened against a soft metal washer 61 the grooves will cut into the washer and form a hermetic seal. A bracket 62 is secured by a screw 63 to the closed end of the ferrule 58 on the A end of the tube and by a screw 64 to an insulating bar 65 which supports a series of gaps in the arc extinguishing fluid; the bracket making electrical contact with the terminal side of the last gap. The other end of the insulating bar is free to move longitudinally on a guide pin 66 when expanded or contracted by a change in temperature. The guide pin is secured to the closed end of the ferrule 58 of the B end of the tube and slidably engages the end of the bar 65. A flexible connector 65a completes the electrical circuit from the terminal side of the last gap to the closed end of the ferrule 58. A plurality of castings 67 made of a conducting material are secured to the insulating bar by the screws 68, Figure 8, and spaced so as to form a series of gaps. Conducting spheres 69 of a non-magnetic material are disposed for closing the gaps and are free to move into sockets 70 parallel to the longitudinal axis of the tube or sockets 71 at right angles to the longitudinal axis of the tube; such movement opening the gaps and consequently breaking the electrical circuit through the tube. Due to the arc extinguishing fluid in the tube, the spheres will move into and out of the sockets with plunger like action. The spheres make a point contact with the contact surface of the gaps. In the closed position of the gaps the arc extinguishing fluid closely surrounds the point contact and since a sphere may be moved thru a fluid with the least amount of disturbance of the fluid, it is evident that as the spheres begin to move away from the contact surfaces the arc extinguishing fluid instantly fills the gaps and prevents any arc from forming.

While the drawings show only one hermetically sealed tube mounted upon the disconnecting switch, it is not proposed to limit this invention to the use of one tube as it is contemplated that a number of tubes having their con-

tact points in series might be mounted in parallel or the tube might be constructed with several rows of contacts within one tube, the contacts being arranged electrically, either in series or multiple depending upon the amount of current which it is desired to carry.

Figures 2 and 4 show the switch of my invention mounted in various positions upon a sustaining structure. The various parts of the switch, which it would be necessary to reassemble in order to adapt the switch for operation in the respective positions, are clearly shown in these figures. For example, assuming the switch to be originally mounted in the horizontal position as shown in Figure 2, the switch parts are assembled as shown more clearly in Figure 1. In this position, the tube 57 is mounted with its B end adjacent the blade contact and its A end adjacent the pivoted end of the blade. The female contact member is carried by the blade, and the male contact member mounted on insulator 3.

If it is now desired to transfer the horizontally mounted switch to a location wherein it will be in a vertical position as shown in Figure 2, the only changes necessary to adapt the switch to the vertical mounting are to turn the tube 57 end for end so that the A end is adjacent the blade contact rather than the B end, and interchange the male and female contact members.

In changing from the vertical mounting shown in Figure 2 to the underslung mounting as shown in Figure 4, the insulators 3-3 are turned end for end and the tube 57 is rotated 180 degrees about its longitudinal axis. It is thus evident that the switch may be readily adapted for any mounting by simply reassembling a few parts. Enlarged views of the tube 57 are shown in Figures 1, 6 and 7 with cut-out portions, the tubes being disposed in their relative positions to correspond to the switch mountings as shown in Figures 2 and 4.

The operation of the switch, when mounted in the horizontal position with the insulators above the base, as shown in Figures 1 and 2, from completely closed position to completely open, and from completely open to completely closed is as follows: The switch is opened by inserting a switch hook into the ring 22 of the switch lock. A firm pull upwardly and toward the hinge end of the switch, will unlatch the switch lock and pull the switch blade out of contact, swinging the switch blade about the pivot pin 11 to the 90 degrees open position. To describe the movement of the fluid switching unit, while the switch blade is being opened, it is best to divide the movement of the switch blade into two parts, that is, from the closed position to substantially 45 degrees open position, and from this position to fully open.

It will be observed that, when the switch blade is in circuit closed position, the tube 57 is downwardly inclined towards its B end and the spheres 69 occupy gap-closing positions, each sphere being in engagement with an upper contact surface formed by the wall of a socket 71 and a lower contact surface formed by the wall of a socket 70. Since the sockets 70 are at this time inclined downwardly towards the gaps the spheres are held in gap-closing position by the action of gravity. Now, as the switch blade is swung to the 45° position, as shown in dotted lines in Figure 1, the lever arm 46 is moved anti-clockwise to a horizontal or dead center position, this movement causing the A end of the

tube 57 to travel downwardly and to the left. Simultaneously with this movement of the A end of the tube, the B end is guided by the anticlockwise movement of link 47 so that this end moves 5 downwardly and to the left. It will be observed, however, that at the 45° position the downward movement of the A end of the tube has been relatively greater than the downward movement of the B end of the tube; that the tube is still 10 slightly downwardly inclined toward its B end; and that during the above described movement of the tube the spheres 69 have remained in gap-closing position, since no forces have acted to change their position. The circuit at this time 15 is through the fluid switching unit, since the circuit through the switch blade has already been opened.

Immediately upon the passage of the switch blade through its 45° position, the arm 46 is 20 moved below its horizontal or dead center position and continues to carry the A end of the tube still further in a downward direction and at the same time causes this end to move to the right instead of to the left as when the arm 46 25 was approaching its dead center position. Moreover, the link 47 is now moving in a clockwise direction which causes the B end of the tube to move upwardly and to the right. As before, it will be observed that the downward movement 30 of the A end of the tube is relatively greater than the upward movement of the B end of the tube.

As a result of this change in the direction of movement of the tube 57 from left to right as the lever arm 46 passes through its horizontal or 35 dead center position, the upper contact surfaces formed by the walls of the sockets 71 are moved away from the spheres 69 with a snap action. At the same instant, the supports for the spheres have changed. Instead of being supported on 40 both the upper and lower contact surfaces as previously, the spheres are now supported only upon the lower contact surfaces. The motion of the tube is now such, by virtue of moving the A end downwardly and to the right and the B end upwardly and to the right, that the lower contact surfaces cause the spheres to move into the sockets 70 leaving the gaps fully open. Moreover, during the movement of the switch blade 45 from the 45° position to the fully open or 90° position, the sockets 70 are rapidly and increasingly downwardly inclined from the gaps, so that the speed of movement of the spheres into the sockets 70 is augmented by the action of 50 gravity.

55 The switch is closed by inserting the switch hook into the ring 22, whereupon a firm quick thrust will swing the blade into closed position where it is automatically locked by the engagement of the latch dog with the contact casting 60 24. Since the movement of the fluid switching unit, when closing the switch blade, is just the reverse of its movement during the opening of the switch blade, a detailed description of the movements of the arm 46, the link 47 and the tube 57 is not deemed necessary.

When the switch blade is in the fully open or 90° position, the spheres 69 are retained at the closed ends of the sockets 70 by the action of gravity, these sockets at this time being downwardly inclined away from the gaps. This condition prevails until the switch blade has passed 70 through the 45° position, at which time the arm 46 has also passed through its horizontal or dead center position and reversed the movement of 75 the tube 57 from left to right, the link 47 revers-

ing its movement from left to right simultaneously therewith. This movement of the tube gives a snap action to the right which forces the closed ends of the sockets 70 against the spheres 69 and drives them into the gaps to initially close the electrical circuit through the liquid switching unit. As the switch blade continues to move from the 45° position, the sockets are rapidly and increasingly inclined downwardly towards the gaps, thereby enabling the force of gravity to augment the speed of movement of the spheres into the gaps. In the fully closed position of the switch blade, the spheres are again held in gap closing position by the action of gravity, and the switch blade now carries the main portion of the current.

Switches embodying the features of this invention have been found to be particularly desirable for interrupting circuits which carry a relatively high order of current. This will be more fully appreciated when the action of the spheres and contacts are considered during the interruption of the circuit. The fact that spheres have been used enables the contacts and spheres to be separated in the arc extinguishing liquid in which they are submerged with a minimum amount of resistance, thereby enabling the gap to be opened at a relatively high speed. The resulting high speed in opening the gap enables a high interrupting capacity to be obtained, as is well known in the art.

As soon as the sphere begins to open the gap a thin film of the arc extinguishing liquid is formed. This film at first is of low resistance and gradually increases as the gap increases 110 and the film of fluid becomes thicker, the result being that when the gaps are fully opened the arc extinguishing fluid in the series of gaps forms a total resistance across which is a potential drop equal to the potential of the total 115 circuit which is being interrupted. It is therefore apparent that by introducing a sufficient number of gaps the voltage to be handled can be divided so that the potential handled by each gap falls well within the physical, chemical and 120 thermal capacity of the electrolytic fluid. Further, the use of spherical members is advantageous in that the members are not subject to electrical magnetic stress which would be present during the rupture of heavy current. Rebounding 125 of the spheres either in opening or closing of the switch is prevented by the plunger action of the spheres in the sockets due to the displacement of the arc extinguishing fluid. Also the action of all the spheres will be simultaneous 130 because of the parallel relationship of the sockets.

The operation of the switch, when mounted in a vertical position as shown in Figure 2, from completely closed to completely open position 135 and from completely open to completely closed again is as follows: The switch is opened by inserting a switch hook into the ring 22 of the switch blade. A firm quick pull on the switch hook unlatches the switch lock and pulls the 140 switch blade out of contact, the blade swinging about the pivot pin 11 to 90° open position. In order, however, that the operation of the fluid switching unit may be more readily understood, the movement of the switch blade will be considered in two parts, that is, from closed position to 45° open position and from this position to fully open position.

Referring to Figures 2 and 7, it will be observed that, when the switch blade is in cir- 150

cuit closed position, the tube 57 is downwardly inclined toward its B end and the spheres 69 occupy gap closing positions, each sphere being in engagement with an upper contact surface in engagement with an upper contact surface 5 formed by the wall of a socket 70, and a lower contact surface formed by the wall of a socket 71. Since the sockets 71 are at this time inclined downwardly toward the gaps, the spheres are held in gap closing position by the action of gravity. Now, as the switch blade is swung to the 45° position, the lever arm 46 is moved clockwise to a vertical or dead center position, this movement causing the B end of the tube 57 to travel downwardly and to the left. Simultaneously with this movement of the B end of the tube, the A end is guided by the clockwise movement of link 47 so that this end moves downwardly and to the left. It will be observed, however, that at the 45° position, the movement to the left of the B end of the tube has been relatively greater than the movement to the left of the A end of the tube; that the tube is still slightly inclined, having almost reached a vertical position; and that during the above described movement of the tube the spheres 69 have remained in gap closing position, since no forces have acted to change their position. The circuit at this time is through the fluid switching unit, since the circuit through the switch blade has already been opened.

Immediately upon the passage of the switch blade through its 45° position, the arm 46 is moved to the left of its vertical or dead center position and continues to carry the B end of the tube still further in a direction to the left, and at the same time causes this end to move upwardly instead of downwardly as when the arm 46 was approaching its dead center position. Moreover, the link 47 is now moving in an anti-clockwise direction which causes the A end of the tube to move upwardly and to the right. As before, it will be observed that the movement of the B end of the tube to the left is relatively greater than the corresponding movement of the A end of the tube.

As a result of this change in the direction of movement of the tube 57 from a downward to an upward direction as the lever arm 46 passes through its vertical or dead center position, the upper contact surfaces formed by the walls of the sockets 70 are moved away from the spheres 69 with a snap action. At the same instant the supports for the spheres have changed. Instead of being supported on both the upper and lower contact surfaces as previously, the spheres are now supported only upon the lower contact surfaces. The motion of the tube is now such, by virtue of moving the B end upwardly and to the left and the A end upwardly and to the right, that the lower contact surfaces will cause the spheres to move into the sockets 71, leaving the gaps fully open. Moreover, during the movement of the switch blade from the 45° position to the fully open or 90° position the sockets 71 are rapidly and increasingly downwardly inclined away from the gaps, so that the speed of movement of the spheres into the sockets 71 is augmented by the action of gravity.

The switch is closed by inserting the switch hook into the ring 22, whereupon a firm quick thrust will swing the blade into closed position, where it is automatically locked by the engagement of the latch dog with the contact casting 24. Since the movement of the fluid switching unit, when closing the switch blade, is just the

reverse of its movement during the opening of the switch blade, a detailed description of the movement of arm 46, link 47 and tube 57, is not deemed necessary.

When the switch blade is in the fully or 90° opened position, the spheres 69 are retained at the closed ends of the sockets 71 by the action of gravity, these sockets at this time being downwardly inclined away from the gaps. This condition prevails until the switch blade has passed through the 45° position, at which time the arm 46 has also passed through its vertical or dead center position and reversed the movement of the tube 57 from a downward direction to an upward direction, the link 47 reversing its movement from a downward to upward direction simultaneously therewith. This movement gives a snap action of the tube to the right which moves the sockets 71 away from the spheres and the upper contact surfaces of the sockets 70 into engagement with the spheres. As the switch blade continues to move from the 45° position the sockets 71 are rapidly and increasingly inclined downwardly toward the gaps, thereby enabling the force of gravity to augment the speed of movement of the spheres into the gaps. In the fully closed position of the switch blade, the spheres are again held in gap closing position by the action of gravity and the switch blade carries the main portion of the current.

The operation of the switch, when mounted in the underslung position, as shown in Figure 4, from completely closed position to completely open, and from completely open to completely closed position is as follows: The switch is opened by means of a switch hook in the same manner as the other mountings of the switch, and for purposes of description the switch blade is likewise considered as having its movement divided into two parts; that is, from fully closed position to the 45° position, and from the 45° position to the 90° or fully open position.

It will be observed, that when the switch blade is in circuit closed position, the tube 57 is downwardly inclined towards its B end and the spheres 69 occupy gap closing positions as shown in Figure 6, each sphere being in engagement with an upper contact surface formed by the wall of a socket 71 and a lower contact surface formed by the wall of a socket 70. Since the sockets 70 are at this time inclined downwardly towards the gaps, the spheres are held in gap closing position by the action of gravity. Now, as the switch blade is swung to the 45° position, the lever arm 46 is moved clockwise to a horizontal or dead center position, this movement causing the B end of the tube 57 to travel upwardly and to the left. Simultaneously with this movement of the B end of the tube, the A end is guided by the clockwise movement of link 47 so that this end moves upwardly and to the left. It will be observed, however, that at the 45° position the upward movement of the B end of the tube has been relatively greater than the upward movement of the A end of the tube; that the tube is still slightly downwardly inclined toward its B end; and that during the above described movement of the tube the spheres 69 have remained in gap closing position since no forces have acted to change their position. The circuit at this time is through the fluid switching unit since the circuit through the switch blade has already been opened.

Immediately upon the passage of the switch

blade through its 45° position, the arm 46 is moved above its horizontal or dead center position and continues to carry the B end of the tube still further in an upwardly direction and

- 5 at the same time causes this end to move to the right instead of to the left as when the arm 46 was approaching its dead center position. Moreover, the link 47 is now moved in an anti-clockwise direction which causes the A end of 10 the tube to move downwardly and to the right. As before, it will be observed, movement of the B end of the tube is relatively greater than the downward movement of the A end of the tube.

As a result of this change of the direction of 15 movement of the tube 57 from left to right, as the lever arm 46 passes through its horizontal or dead center position, the upper contact surfaces formed by the walls of the sockets 71 are forced against the spheres which are thereby driven 20 into the sockets 70. At the same time the upper contact surfaces move away from the spheres and the lower contact surfaces swing upwardly to meet the spheres. At the same instant the 25 supports for the spheres have changed. Instead of being supported on both the upper and lower contact surfaces as previously, the spheres are now supported only upon the lower contact surfaces.

Moreover, during the movement of the switch 30 blade from the 45° position to the fully open or 90° position, the sockets 70 are rapidly and increasingly downwardly inclined away from the gaps, so that the speed of movement of the spheres into the sockets 70 is augmented by the 35 action of gravity.

The switch is closed in the same manner as 40 previously described, and since the movement of the arm 46, link 47 and tube 57 is just the reverse of their movement in opening the switch, their movements will not again be described in detail.

When the switch is in the fully or 90° opened 45 position, the spheres 69 are retained at the closed ends of the sockets 70 by the action of gravity, these sockets at this time being downwardly inclined away from the gaps. This condition prevails until the switch blade has passed through the 45° position, at which time the arm 50 46 has also passed through its horizontal or dead center position and reversed the movement of the tube 57 from left to right, the link 47 reversing its movement from left to right simultaneously therewith. This movement gives a snap action of the tube to the right, which 55 brings the upper contact surfaces formed by the walls of the sockets 71 into engagement with the spheres. As the switch blade continues to move from the 45° position, the sockets 70 are rapidly and increasingly inclined downwardly towards the gaps, thereby enabling the force of gravity 60 to augment the speed of movement of the spheres into the gaps. In the fully closed position of the switch blade, the spheres are again held in gap closing position by gravity and the switch blade carries the main portion of the 65 current.

It is therefore evident that by the use of this 70 invention a disconnecting switch is obtained which is adapted for mounting in any position merely by reassembling of the switch parts. The switch is provided with full floating contact members which are self aligning, having a multiplicity of positive contact points. This invention also includes a disconnecting switch which 75 may be opened in a very short period of time,

a switch blade opening the main portion of the circuit and a fluid switching unit which is shunted around the switch blade opening the remaining portion of the circuit.

I am aware that many changes may be made, 80 and numerous details of construction may be varied through a wide range without departing from the principles of this invention, and I therefore, do not purpose limiting the patent granted hereon, otherwise than necessitated by 85 the prior art.

I claim as my invention:

1. In a device of the character described, a main air break switch mounted for arcuate movement, an auxiliary fluid break switch floatingly mounted and having a tilting and translatory movement, said latter switch having parts arranged to open and close a circuit there-through in response to said movement, and means connecting said air break switch to said 95 fluid break switch for imparting said movement thereto.

2. In a disconnecting switch, a sheath having a plurality of sockets therein, contact members disposed in said sockets, resilient means encircling said sheath for retaining said members in 100 said sockets, and a contact plunger for insertion into said sheath for engaging said members.

3. In a disconnecting switch, a female contact 105 member comprising a sheath having a plurality of sockets therein, balls disposed in said sockets and projecting past the inner wall of said sheath, current carrying strips secured to one end of said sheath and in engagement with said balls, 110 resilient means surrounding said strips for forcing said strips and balls inwardly, and a male contact member for insertion into said sheath for engaging said balls.

4. In an electric switch, a female contact 115 member comprising a sheath having a plurality of sockets therein, balls disposed in said sockets and projecting past the inner wall of said sheath, current carrying strips secured to 120 said sheath and engaging said balls, resilient means for forcing said strips and balls inwardly, and a male contact member for engaging said balls.

5. In a disconnecting switch, the combination 125 including a movable blade, a movable circuit making and breaking member, said member comprising a container, a plurality of insulated conducting members in said container, means for electrically connecting said members when said container is moved in one direction and disconnecting said members when said container is moved in another direction, and movable connecting means between said switch blade and said container for moving said container when the switch blade is moved.

6. In a disconnecting switch, the combination 130 including a movable blade, a movable circuit making and breaking member, said member comprising a container, a plurality of current carrying members having gaps therebetween, 135 balls movable with respect to said members to close said gaps when said balls are moved in one direction and open said gaps when moved in another direction, and means for moving said balls responsive to the movement of said 140 blade.

7. In a disconnecting switch, the combination 145 including a movable blade, a movable circuit making and breaking member, said member comprising a container, a plurality of current 150

carrying members having gaps therebetween, said members having sockets, freely moving balls in said sockets, and means responsive to the movement of said blade for moving said container to cause the balls to bridge said gaps or move into said sockets.

8. In a disconnecting switch, the combination including a movable blade, a movable circuit making and breaking member, said member comprising a container, an arc extinguishing fluid sealed in the container, a plurality of current carrying members having gaps therebetween, said members having sockets communicating with said gaps, freely moving balls in said sockets, and means responsive to the movement of said blade for moving said container to cause the balls to bridge said gaps or move into said sockets.

9. In a disconnecting switch including means for opening and closing a circuit, said means comprising a movable contact sheath having a plurality of sockets therein, balls disposed in said sockets, resilient means surrounding said sheath for retaining said balls in the sockets, and a stationary contact member arranged to receive the sheath thereover and make contact with said balls.

10. A circuit controlling device comprising a movable support, a series of spaced contact members secured to said support and electrically insulated relative to each other, and a plurality of members floatingly associated with said contact members and adapted to simultaneously occupy an open circuit or closed-circuit position relative to said contact members depending upon the movement of said support.

11. A circuit controlling device comprising a movable support, a series of contact members secured in longitudinal alignment to said support in spaced-apart relationship, and movable contact members for bridging the space between said contact members, said movable contact members being constrained for movement from the bridging position in a direction parallel to the longitudinal axis of said support and at right angles to said axis, said movement depending upon the direction in which said support is moved.

12. A circuit controlling device comprising a movable support, a series of current carrying members secured in longitudinal alignment to said support in spaced-apart relationship, movable contact members for bridging the space between said current carrying members, said current carrying members being constrained for movement from the bridging position in a direction parallel to the longitudinal axis of said support and at right angles to said axis, said movement depending upon the position of said support, and means for moving said support in such a manner as to cause the contact members to move simultaneously.

13. A switch comprising a movable support, a plurality of spaced contact members secured to said support in end to end relationship and having sockets in the adjacent ends, the sockets in one set of corresponding adjacent ends being disposed at an angle to the sockets in the other set of corresponding adjacent ends, and balls at adjacent ends of the contact members to connect said members and establish an electric current therethrough when the support is in one position, and to open said circuit when the support is moved to another position by moving

into either of said sets of sockets depending on the direction of motion of said supports.

14. A switch comprising a movable support, a plurality of spaced contact members secured to said support in end to end relationship and having sockets in the adjacent ends, the sockets in one set of corresponding adjacent ends being disposed at an angle to the sockets in the other set of corresponding adjacent ends, balls at the adjacent ends of the contact members to connect said members and establish an electric circuit therethrough when the support is in one position, and to open said circuit when the support is moved to another position by moving into either of said sets of sockets depending on the direction of motion of said support, and means for moving said support in such a manner that the balls are moved to circuit opening and circuit closing positions with a snap action.

15. A switch comprising a hermetically sealed container mounted for translatory movement, a support within said container, a plurality of spaced contact members secured to said support in end to end relationship and having sockets in the adjacent ends, the sockets in one set of corresponding adjacent ends being disposed at an angle to the sockets in the other set of corresponding adjacent ends, and balls at the adjacent ends of the contact members to connect said members and establish an electric current therethrough when the container is in one position, and to open said circuit when the container is moved to another position by moving into either of said sets of sockets, depending upon the direction of motion of said container, the making and breaking of said circuit being out of contact with the atmosphere.

16. A switch comprising a movable support, a pair of spaced current carrying members secured to said support, one of said members having a socket, a ball in said socket movable into and out of engagement with the other of said current carrying members, an oscillatable arm connected to one end of said support, a swingable link connected to the other end of said support, said arm and link being relatively disposed in such a manner that movement of the arm thru its dead center position in cooperation with the movement of said link will force said ball into and out of engagement with both of said current carrying members.

17. A switch comprising a movable support, a pair of spaced current carrying members secured to said support, one of said members having a socket, a ball in said socket movable into and out of engagement with the other of said current carrying members, an oscillatable arm connected to one end of said support, a swingable link connected to the other end of said support, said arm and link being relatively disposed in such a manner that movement of the arm thru its dead center position in cooperation with the movement of said link will force said ball into and out of engagement with both of said current carrying members and tilt said current carrying members so that the movement of said ball in the socket is augmented by the action of gravity.

18. A switch comprising a movable support, a pair of spaced current carrying members secured to said support, one of said members having a socket, a ball in said socket movable into and out of engagement with the other of said current carrying members, an oscillatable arm connected to one end of said support, a swingable link connected to the other end of said sup-

port, said arm and link being arranged for movement in arcs which are substantially in quadrature, whereby said ball is caused to connect and disconnect said current carrying members.

5 19. A switch comprising a movable support, a pair of spaced current carrying members secured to said support, one of said members having a socket, a ball in said socket movable into and out of engagement with the other of said current carrying members, an oscillatable arm connected to one end of said support, a swingable link connected to the other end of said support, said arm and link being of such relative lengths that one end of said support is laterally moved 10 15 a greater amount than the other end of said support.

20. A switch comprising a stationary contact member, a pivotally mounted switch blade having a forked free end, each leg of said fork having 20 a plurality of spaced apertures, a movable contact member having a projecting portion extending between the legs of said fork, and pins extending transversely through said projecting portion, said pins having their ends loosely disposed in 25 said apertures.

21. In a disconnecting switch, a cylindrical sheath having a plurality of peripheral sockets, spherical contact members disposed in said sockets, a coiled spring surrounding said sheath 30 for retaining said spherical contact members in said sockets, and a contact plunger insertable into said sheath for engagement with said spherical contact members.

22. In a disconnecting switch, a cylindrical sheath having a plurality of peripheral sockets, spherical contact members disposed in said sockets, a coiled spring surrounding said sheath for retaining said spherical contact members in 35 said sockets, and a contact plunger insertable 40 into said sheath for engagement with said spherical contact members, and means for relatively moving said contact sheath and plunger axially when engaged and in an arc when disengaged.

45 23. In a device of the character described, the combination including a movable blade, an arm swingable with said blade, an oscillatably mounted link, and means having parts arranged and positioned in such a manner as to open and 50 close an electrical circuit therethrough in response to a translatory movement, said link and arm cooperating to support said means and move said means when the blade is moved.

24. In a disconnecting switch, a switch blade 55 mounted for arcuate movement, a contact member at the free end of said blade, a stationary contact, said contacts being engageable and disengageable by relative axial movement thereof, and a floating connection between the first con-

60

tact and blade to enable relative axial movement of the contacts when engaged and arcuate movement of the first contact with the blade when the contacts are disengaged.

25. In a disconnecting switch, a switch blade 80 mounted for arcuate movement, a plunger member forming a contact, a tubular member for axially receiving said plunger, one of said members being carried by the blade and the other being fixedly mounted to cooperate with said one of said members, and a floating connection 85 between the blade and the member thereon, whereby the tubular member may axially receive the plunger member during an arcuate movement of the blade.

26. As an article of manufacture, a unitary replacement switching unit comprising a sealed tubular container, external contact members at the ends of the container, a support in the container, a series of spaced current-carrying members secured to the support and electrically insulated relative to each other, the outermost of said members being respectively connected to the contact members of the container, a plurality of members in the container operatively 100 associated with the current-carrying members and adapted to bridge the current-carrying members, when the container is moved from one position to another.

27. As an article of manufacture, a unitary 105 replacement switching unit comprising a sealed tubular container, external contact members at the ends of the container, a support in the container, a series of current-carrying members secured to said support in longitudinal alignment 110 in spaced apart relationship and electrically insulated from each other, the outermost of said members being connected to the contact members of the container, movable members adapted to bridge the space between the current-carrying members, said current-carrying members being constrained for movement from their bridging position in a direction parallel to the longitudinal axis of the container and at right angles to said axis in response to a predetermined movement of the container.

28. As an article of manufacture, a self-container switching unit comprising a sealed tube having end contacts outside the tube, a support of insulating material in the tube, a plurality of 125 current-carrying members secured to said support in a manner to form separating gaps therebetween, said members having sockets in communication with the gaps, freely moving balls disposed so as to bridge the gaps and move into 130 the sockets, and connections from the end contacts of the tube to the outermost of the current-carrying members.
